ings into which are threaded tubular members 28 having valve seats at their upper ends that are engaged and closed by the lower conical ends 29 of the screws 30 which 5 extend through the upper side of the cylinder 25 for engagement with the valve seats to control the supply of liquid fuel to the burner tips. A pipe section 31 is threaded upwardly through the block 8 and within 10 which the tubular member 28 is received as clearly shown, while an elbow 32 joins the lower end of the vertical pipe 31 to the horizontal pipe 33. A wick 34 of any desired form is positioned in the pipe 33 and the oil or other burning fluid fed from the cylinder 25 passes downwardly through the tubular member 28 to be absorbed by the wick 34.

The burner is mounted in a protective casing 20 consisting of a substantially reversed L-shaped member 35 having the lower front wall thereof turned upwardly as at 36 to provide a lip so that the material contained within the casing and surrounding the 25 burner pipes will be prevented from falling out. It is preferably desired to fill the burner pipe casing with clay, sand or similar material so that the flame from the wicks 34 will not be blown backwardly into 30 the casing by the fan wheel 16.

The platform 9 carries an operator's seat 37 while the rear end of the frame bars 5 are supported upon rollers 38 mounted in arms 39 that are fixed to the horizontal 45 shaft 42 journaled in the bearings 41 upon the platform 9. A crank handle 42 is fixed to the shaft 40 and carries a tensioned locking rod 43 adapted for engagement with the segment rack 44 so that by shifting the 50 crank handle 42 rearwardly from the position shown in Fig. 1, the supporting arms 39 of the rear wheels 38 will be moved to a substantially vertical position and elevate the rear end of the frame so as to regulate 55 the distance between the burner and the ground. In order to prevent side air drafts from interfering with the usual operation of the burners, there are provided side wind-shields 45 supported as by bolts 46 to the 60 side bars 5 of the frame with the lower edges thereof extending slightly below the burner as is indicated in Fig. 1.

By the forward propulsion of the machine, the land roller 10 is driven in the direction as indicated by the arrow in Fig. 1 65 which communication is transmitted to the fan blower 16 by the sprocket and gear connection above described so that the fan blower will be rotated in the direction as indicated by the arrow. The air is blown 70 downwardly upon the ground by the particular disposition of the blades 17 and the flame from the wick 34 is accordingly downwardly directed into direct contact with 75 stalks, weeds or other rubbish to be burned.

The supply of fuel to the wick 34 may be controlled by the needle valve 30 while the rear end of the machine may be raised and lowered in the manner as above described.

While the invention is herein shown and 70 described as a complete machine including the land roller 16, it is to be understood that the device may be readily applied to the present construction of land roller by the simple addition of a sprocket gear upon the 75 land roller bearing and the operation thereof will be identical.

While the form of the invention herein 80 shown and described is what is believed to be the preferred embodiment thereof, it is nevertheless to be understood that various 85 forms, modifications and arrangements of the parts may be made without departing from the spirit and scope of the invention as claimed.

What I claim as new is:—

1. A machine of the class described comprising a supporting frame, a burner carried thereby, means for supplying fuel to the burner, means for directing the flame 90 of the burner downwardly, and a land roller positioned forwardly of the burner and adapted to operate the flame directing means.

2. A machine of the class described comprising a supporting frame, a burner carried thereby, means for supplying fuel to the burner, means for raising and lowering the frame to vary the position of the burner relative to the ground, means for directing the flame of the burner downwardly and a 95 land roller positioned forwardly of the burner adapted to operate the last named means.

3. A machine of the class described comprising a supporting frame, a burner carried thereby, means for feeding fuel to the burner, means for directing the flame of the burner downwardly, a land roller for supporting the forward end of the frame constituting driving means for the flame 105 directing means, and means positioned at the rear end of the frame for raising and lowering the frame to vary the distance between the burner and ground.

4. A machine of the class described comprising a frame, a burner carried thereby, a fan journaled in said frame forwardly of the burner, and a land roller positioned forwardly of the fan adapted to operate the fan.

5. A machine of the class described, comprising a supporting frame, a land roller journaled therein, a stub shaft journaled in said frame, sprocket and chain connections between the stub shaft and land roller, a fan 125 wheel journaled in said frame, gear connections between said fan wheel and the stub shaft, the fan wheel being positioned rearwardly of the land roller, a burner positioned rearwardly of the fan wheel, wind- 130

shields carried by the sides of the frame inclosing the lower side of the fan wheel and the burner, a fuel tank for supplying fuel to the burner, and rear supporting wheels carried by the frame, said wheels being adjustable to regulate the distance between the burner and the ground.

6. A machine of the class described comprising a supporting frame, supporting means therefor, a burner carried by said frame, said burner including a fuel tank and a fuel cylinder, a plurality of needle valves associated with said cylinder, a plurality of reversed L-shaped burner pipes carried by said frame and in communication with said fuel cylinder, a protective casting inclosing said L-shaped pipes, and a fan blower associated with said burner for directing the flame downwardly.

7. A machine of the class described, comprising a supporting frame, a burner carried thereby, said burner including a plurality of burner nozzles, a single casing for

the nozzles, a heat refractory material for the casing surrounding the nozzles, means carried by the casing for preventing the escape of the filling material, valve-controlled means for feeding fuel to the burners, and a fan blower associated with the burner for directing the flame downwardly.

8. A machine of the class described, comprising a supporting frame, a burner supported carried thereby, a plurality of reversed L-shaped burner elements fixed in said support, an oil tank, a horizontal cylindrical member associated with said tank and resting upon said support, tubular members carried by the cylindrical member and extending downwardly therefrom to be freely received within said reversed L-shaped burners, and a fan associated with said burner for directing the flame downwardly.

In testimony whereof I affix my signature,

AMUND E. TWEIT.
